(57) **CLAIM**

The ornamental design for mounting bracket, as shown and described.

DESCRIPTION

FIG. 1 is a top perspective view of a mounting bracket illustrating a first embodiment of our new design; FIG. 2 is a bottom perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a left side elevation view thereof; FIG. 8 is a right side elevation view thereof; FIG. 9 is a top perspective view of a mounting bracket illustrating a second embodiment of our new design; FIG. 10 is a bottom perspective view thereof; FIG. 11 is a front elevation view thereof; FIG. 12 is a rear elevation view thereof; FIG. 13 is a top plan view thereof; FIG. 14 is a bottom plan view thereof; FIG. 15 is a left side elevation view thereof; FIG. 16 is a right side elevation view thereof; FIG. 17 is a top perspective view of a mounting bracket illustrating a third embodiment of our new design; FIG. 18 is a bottom perspective view thereof; FIG. 19 is a front elevation view thereof; FIG. 20 is a rear elevation view thereof; FIG. 21 is a top plan view thereof; FIG. 22 is a bottom plan view thereof; FIG. 23 is a left side elevation view thereof; and, FIG. 24 is a right side elevation view thereof. Dashed lines in the drawings illustrate portions of the mounting bracket. Dash-dot-dash boundary lines in FIGS. 1-3 illustrate the boundary between claimed and unclaimed edge surfaces. All broken lines form no part of the claimed design.

1 Claim, 24 Drawing Sheets
